PROCESS FOR HYDROCARBON CONVERSION
IN PRESENCE OF ADDED TERPENES PLUS
NONMETALLIC BROMINE COMPOUNDSHillis O. Folkins, Skokie, Ill., assignor to The Pure
Oil Company, Chicago, Ill., a corporation of
OhioNo Drawing. Application March 8, 1946,
Serial No. 653,125

20 Claims. (Cl. 196—52)

1

This invention relates to a method for conversion of hydrocarbons and more particularly to the conversion of liquid hydrocarbons boiling above the gasoline range to hydrocarbons boiling within the gasoline range or to the conversion of hydrocarbons boiling within the gasoline range to hydrocarbons of higher octane value.

I have discovered that non-halogen-containing terpenes, particularly cyclic terpenes and derivatives thereof, when used together with bromine, hydrogen bromide, phosphorus bromides or organic bromine compounds, particularly brominated aliphatic compounds or cyclic compounds containing bromine substituted in an aliphatic chain, which are free of metals and metalloids, not only act as sensitizers to increase the yield of gasoline-boiling hydrocarbons in the cracking of higher boiling hydrocarbon oils, but appreciably improve the octane rating of the resulting gasoline.

Terpenes and their derivatives when used alone are effective to a somewhat limited extent in improving both yield of gasoline and the octane value of the resulting gasoline produced in the cracking of hydrocarbon oils. Bromine and bromine compounds likewise are more effective as sensitizers than terpenes in improving the yield of gasoline in the cracking of hydrocarbon oils. However, bromine and bromine compounds when used in amounts in excess of about 0.1% by weight (based on bromine equivalent) of the oil undergoing cracking, have been found to deleteriously affect the lead susceptibility of the resulting gasoline.

One of the objects of this invention is to provide an improved method for converting hydrocarbons boiling above the gasoline boiling range to hydrocarbons boiling within the gasoline boiling range.

Another object of the invention is to provide an improved method for increasing the octane value of gasoline boiling hydrocarbons formed in the cracking of hydrocarbon oils.

Still another object of the invention is to increase the yield of gasoline boiling hydrocarbons from higher boiling hydrocarbons and to improve the octane value of the resulting gasoline.

Other objects of the invention will become manifest from the following description.

In accordance with my invention, hydrocarbon oil is mixed with a small amount of a terpene or derivative thereof and with a small amount of bromine, hydrogen bromide, a phosphorus bromide or organic bromine compound and subjected to cracking temperatures which may be

2

approximately 650 to 1200° F., under pressures which may be atmospheric or superatmospheric.

As organic bromine compounds for use as sensitizers, I prefer to use non-metal containing compounds and more particularly brominated aliphatic compounds or cyclic compounds containing a bromine-substituted aliphatic side-chain. As examples of bromine compounds which may be used are ethylene dibromide, ethyl bromide, propylene dibromide, allyl bromide, acetyl bromide, bromo-acetic acid, beta-bromo-ethyl ethyl ether and benzyl bromide. Bromine compounds which vaporize at cracking temperature and pressure or which decompose into bromine or bromine compounds which vaporize under cracking conditions are preferred.

Bromine or bromine compounds may be present in the mixture undergoing cracking in amounts equivalent to about 0.005 to 1% by weight of bromine, based on the total charge, but I prefer to use bromine or bromine compounds in an amount not exceeding 0.1% by weight of bromine equivalent since larger amounts of bromine or bromine compounds generally have a deleterious effect on the lead susceptibility of the resulting gasoline.

Terpenes, derivatives thereof, such as esters, ethers, alcohols and the amino, nitro, alkyl, aryl and aralkyl derivatives in which these groups are substituted for one or more hydrogen atoms in the terpene molecule, may be used together with bromine or bromine compounds. Substances rich in terpenes or their derivatives, such as turpentine and citronella oil may be used in place of pure terpenes and their derivatives.

Examples of terpenes, derivatives thereof, and substances containing the aforesaid which may be used are as follows: alpha pinene, dipentene, alpha terpinene, delta³ carene, sabinene, camphane, ocimene, myrcene, turpentine and citronella oil. The terpenes, their derivatives and substances containing the same, may be used in concentrations ranging from approximately .01 to 3% by weight of the charge.

Although cracking may be carried out at atmospheric pressure, I prefer to crack under superatmospheric pressures upward of 300 pounds per square inch, since higher yields of desired products are obtained under high super-atmospheric pressure.

The sensitizers may be mixed with the hydrocarbons to be charged to the process prior to the entrance thereof into the reaction zone or the sensitizers may be flash-injected directly into the reaction zone after heating sufficiently

to either melt a normally solid substance or to vaporize a normally liquid or solid substance.

data and results of these runs conducted at atmospheric pressure.

5.....	Atm.....	979	164.0	Bromine (0.2% by wt.)	148.4	15.2	16.8	14.9	75.1	75.8	9.3	1.174
6.....	Atm.....	977	164.4	(Bromine (0.1% by wt.)	153.2	12.1	15.1	13.7	78.5	79.0	7.3	1.120
7.....	Atm.....	977	164.0	Turpentine (1% by wt.)	147.6	16.6	18.9	17.7	72.3	72.2	10.1	1.186
8.....	Atm.....	977	164.0	Bromine (0.1% by wt.)	152.4	12.3	15.1	13.1	78.6	79.4	7.5	1.130
9.....	Atm.....	981	165.6	Turpentine (2% by wt.)	150.0	15.0	16.1	14.7	75.8	76.2	9.1	1.159
10.....	Atm.....	975.2	164.0	Bromine (0.1% by wt.)	149.6	13.7	16.1	14.6	76.4	77.0	8.4	1.129

Where flash-injection is practiced, care should be exercised not to heat the sensitizers above their decomposition temperature prior to injection into the reaction zone.

In order to demonstrate the effectiveness of the combination sensitizer, a series of runs was made in a continuous laboratory apparatus using Pennsylvania gas oil as charging stock. The gas oil had the following characteristics:

Percent by weight boiling up to 400° F..... 1.0 35
Gravity A. P. I..... 39.8
Sp. gr..... 0.8260
Wt. lbs. per gal..... 6.878

From an examination of the data in Table I it will be seen that both bromine and turpentine when used alone increase the yield of liquid hydrocarbons boiling up to 400° F. The results further show that there is no advantage in using 30 2% of turpentine instead of 1% insofar as yield is concerned. The results in general show that the combination of bromine and turpentine gives a higher yield of lower boiling hydrocarbons than does either the bromine or turpentine alone.

The results of the runs conducted under superatmospheric pressure are recorded in Table II.

A series of runs was carried out at atmospheric pressure and at a temperature of approximately 525° C. (977° F.). Another series of runs was carried out at a pressure of 500 pounds per square inch and at approximately 475° C. (877° F.). In order to form a basis of comparison, runs were made in which (1) no sensitizer was used; (2) turpentine alone was used; (3) bromine alone was used; and (4) both bromine and turpentine were used. Table I gives the tabulated 75

From an examination of the data recorded in Table II, it will be seen that from a yield standpoint, there is no advantage in using turpentine in conjunction with bromine, since bromine alone under the conditions of the reaction gave at least as good a yield as the combination sensitizer. However, an unusual result was obtained with respect to octane number appreciation. This can be readily seen by comparison of the data for runs 11, 13, 14 and 19. Bromine in the amount of .01% when used alone and turpentine in the amount of 1% when used alone have very little effect on the octane rating of the gasoline. However, the combination of the two in-

creases the octane rating about two numbers. By using 0.05% by weight of bromine together with 1 to 2% by weight of turpentine, not only was the octane rating of the gasoline materially increased over the octane number of the gasoline produced without sensitizer and that produced with only a single sensitizer, but the lead susceptibility was also markedly improved. This result is remarkable because increase in the amount of turpentine above 2% produces no appreciable effect either as to yield or octane number over that obtained with 2%, and increase in the amount of bromine above 0.1% deleteriously affects the lead susceptibility of the gasoline. Thus, by using the combination of a very small amount of bromine with turpentine, not only are the yields of gasoline over those obtained without sensitizer considerably improved, but the octane rating and lead susceptibility are higher than can be obtained by using either bromine or turpentine alone.

Another series of runs was made to demonstrate the effect of the combination of phosphorus tribromide and turpentine as a sensitizer in the cracking of mineral oils. Pennsylvania gas oil was cracked in the same laboratory apparatus used for making the runs recorded in Tables I and II, at temperatures of 525° C. and atmospheric pressure. The data for the various runs is recorded in Table III.

or the fluid type. When applying my invention to known types of cracking operations, it is merely necessary to provide feeding and proportioning means for feeding sensitizer to the hydrocarbons undergoing cracking.

It is claimed:

1. The method of cracking hydrocarbon liquids to gasoline boiling range hydrocarbons comprising subjecting said liquids to cracking conditions of time, temperature and pressure in the presence of a small amount of a substance, effective to sensitize the reaction materially, selected from the group (1) consisting of bromine, hydrogen bromide, phosphorus bromides and metal- and metalloid-free organic bromine compounds, and a small amount of a substance selected from the group (2) consisting of halogen-free terpenes and their derivatives.
- 10 2. Method in accordance with claim 1 in which the substance from group (1) is bromine.
3. Method in accordance with claim 1 in which the substance from group (2) is a terpene.
- 15 4. Method in accordance with claim 1 in which the substance from group (1) is bromine and the substance from group (2) is a terpene.
5. Method in accordance with claim 1 in which the substance from group (2) is a terpene-containing material.
- 20 6. Method in accordance with claim 1 in which the substance from group (2) is a pinene-con-

From an inspection of Table III it is apparent that phosphorus tribromide alone considerably enhances the yield of gasoline per pass obtained, but when used in amount of 0.1% has practically no effect on the octane number of the gasoline and in amounts of 0.5% has a deleterious effect on the octane number of the gasoline. Turpentine when used alone has only a very slight effect in increasing yield of gasoline, but is more effective in improving the octane number than phosphorus tribromide. However, when the combination of phosphorus tribromide and turpentine is used, the yields of gasoline are not only increased above those yields of phosphorus tribromide or turpentine alone, but the octane numbers are considerably enhanced. Note particularly run No. 27 which gave an octane two and one-half numbers above the blank.

It will be seen, therefore, that my invention accomplishes a two-fold improvement in cracking of hydrocarbon oils by increasing the yield of gasoline and by increasing the octane rating and improving lead susceptibility.

My invention is applicable to conventional thermal cracking operations in which no catalyst is used and also to solid catalyst cracking operations of the stationary and moving bed type.

taining material.

- 50 7. Method in accordance with claim 1 in which the substance from group (1) is bromine and the substance from group (2) is turpentine.
8. Method in accordance with claim 1 in which the substance from group (1) is a metal- and metalloid-free organic compound containing a brominated aliphatic chain.
- 55 9. Method in accordance with claim 1 in which the substance from group (1) is a brominated aliphatic compound.
10. Method in accordance with claim 1 in which the bromine equivalent of the group (1) substance is between 0.005 and 1% by weight of the total charge and the group (2) substance is present in amount equal to approximately .01 to 60 3% by weight of the total charge.
11. Method in accordance with claim 1 in which the bromine equivalent of the group (1) substance is between 0.005 and 0.1% by weight of the total charge and the group (2) substance is present in amounts equal to approximately .01 to 3% of the total charge.
- 65 12. The method of cracking hydrocarbon oils to liquid hydrocarbons boiling within the gasoline boiling range comprising subjecting said hydrocarbons to temperatures of the order of 650 to

1200° F. in the presence of a small amount of bromine and a small amount of turpentine for a period of time sufficient to effect substantial cracking of said oil, the amount of bromine and turpentine being sufficient to effect a material sensitization of the reaction.

13. The method in accordance with claim 12 in which the bromine is present in amounts between 0.005 and 0.1% by weight of the charge.

14. The method of cracking hydrocarbon oils to liquid hydrocarbons boiling within the gasoline boiling range comprising, subjecting said hydrocarbons to temperatures of the order of 650° to 1200° F. in the presence of 0.005 to 0.1 per cent by weight of bromine, and 0.01 to 3 per cent by weight of turpentine. 15

15. The method of cracking hydrocarbon oils to liquid hydrocarbons boiling within the gasoline boiling range comprising, subjecting said hydrocarbons to a temperature of about 887° F., and a pressure of about 500 pounds per square inch in the presence of about 0.01 to 0.05 per cent by weight of bromine and about 0.5 to 2 per cent by weight of turpentine.

16. Method in accordance with claim 1 in which the substance from group (1) is a phosphorus bromide. 25

17. Method in accordance with claim 1 in which the substance from group (1) is phosphorus tribromide and the substance from group (2) is turpentine. 30

18. The method in accordance with claim 1 in which the substance from group (1) is ethylene dibromide.

19. The method in accordance with claim 1 in which the substance from group (1) is ethylene dibromide and the substance from group (2) is turpentine.

20. The method of cracking hydrocarbon oil comprising subjecting said oil to suitable cracking conditions of time, temperature and pressure in the presence of phosphorus tribromide in an amount not in excess of approximately 0.1% by weight and turpentine in an amount not in excess of approximately 1% by weight.
